CLAIM

The ornamental design for an electric grinder as shown and described.

DESCRIPTION

1. Electric grinder
- 1.1 : Perspective
- 1.2 : Front
- 1.3 : Back
- 1.4 : Top
- 1.5 : Bottom
- 1.6 : Left
- 1.7 : Right

An electric grinding tool used to grind objects into fine particles or powder.

The broken lines show portions of the electric grinder that form no part of the claimed design.
